M. P. STRETAUSKY
COAL MINING APPARATUS

Filed July 24, 1920

FIG. 2.

FIG. 1.

Inventor

Michael P. Stretausky,

By

Watson, Peck, Morse & Grindle,
Attys

UNITED STATES PATENT OFFICE.

MICHAEL P. STRETAUSKY, OF PARSONS, PENNSYLVANIA.

COAL-MINING APPARATUS.

Application filed July 24, 1920. Serial No. 398,643.

To all whom it may concern:

Be it known that I, MICHAEL P. STRETAUSKY, a citizen of the United States, residing at Parsons, Luzerne County, State 5 of Pennsylvania, have invented certain new and useful Improvements in Coal-Mining Apparatus, of which the following is a specification.

This invention relates to coal mining apparatus particularly to such apparatus used in drilling holes in the coal in preparation for blasting operations. The great bulk of the coal mined is loosened by blasting with powder or dynamite, the holes into which 10 the explosive is placed being drilled by power drills manually manipulated by the miners. The most satisfactory type of power drill utilized is operated by compressed air but this has the well known disadvantage of subjecting the operator to excessive shock which, in time often results in serious injury to the nervous system. To 15 cut down the shock to the minimum the coal miners generally utilize drills of small diameter, such as rock drills, instead of the coal drills especially provided for this purpose, which are considerably larger in diameter. The resulting hole being of small diameter, the desired breaking effect in 20 blasting can only be obtained by the use of dynamite instead of black powder inasmuch as an amount of the black powder sufficient for the purpose cannot be placed in the small sized hole. Dynamite, being 25 a much more powerful explosive than black powder, pulverizes the coal to a much greater extent and causes great wastage, and it also burns the coal in an objectionable manner.

30 The object of the present invention is to provide a simple and inexpensive apparatus to be used in conjunction with the compressed air drills now in common use, whereby the drills may be used without shock to 35 the operator enabling him to drill a hole of any desired size and which permits the operator to put any desired pressure on the drill to obtain a maximum drilling speed.

40 One embodiment of the invention will be disclosed in the following description when taken with the accompanying drawings in which,

Figure 1 is a side view of the apparatus as set up in a mine, and

Figure 2 is a top view of the same, partly broken away.

A pneumatic drill of any usual construction is indicated at 10 in the drawings and this drill rests upon a table 11 having a 55 supporting leg 12 secured to its forward end and pivotally supported at its rear end upon a cross piece 13, the ends of which are provided with attached supporting legs 14. Table 11 is provided with a series of 60 holes 15 and cross piece 13 has a series of holes 16 extending longitudinally thereof, the holes 15 and 16 being of the same size 65 and adapted to receive a pin 17 which constitutes a pivot about which the table 11 70 may be swung. The table 11 may be adjusted forwardly and rearwardly and from side to side by removing the pin 17, bringing any two holes in the table and cross piece into registry and reinserting the pin. 75 Adjustable mine jacks 18 extending from floor to roof are positioned in rear of the cross piece to prevent the rearward movement thereof in the operation of the device.

Positioned in rear of the table 11 and its 80 supporting members is a windlass 19 of any suitable type, anchored to the floor as by a chain and pin or fastened to a mine timber, and the windlass and pneumatic drill are connected by means of a rope or other flexible connector 20 having one end secured to the drill and the other wound on the drum of the windlass, the rope passing thru an aperture near the forward end of the table 11 and over a pulley 21 located at that point. 85

In the operation of the apparatus one operator stands beside the table 11 and guides the drill, which is resting therein, and a second operator turns the handle of the windlass to advance the drill toward the 90 wall of coal which it faces. Any desired pressure may be placed on the drill point by the windlass operator. Obviously neither operator is subjected to the shock of the drill and in case a hemp rope is utilized 95 but little vibration is conveyed to the windlass due to the elasticity of the rope. The table may be swung about pivot 17 or moved from side to side in boring holes at different points and at different angles.

Having thus described the invention what

is claimed as new and desired to be secured by Letters Patent is:

1. In drilling apparatus of the class described, a power drill, a horizontal support having a plane surface on which said drill freely rests, a leg below the forward end of said support, a horizontal member arranged transversely of and supporting the rear of said support, adjustable means for connecting said support and said member, means preventing rearward movement of said member, a windlass adapted to be fastened to the mine floor, and a flexible member connecting said windlass and said drill and passing around the forward end of said support.
2. In coal mining apparatus, in combination, an air drill of the manually operated

type, a board on which the drill freely rests, a leg adapted to support the forward end 20 of said board, a horizontal member supported at each end by a leg and arranged transversely of the board to support its rear end, holes in said board and member, a pin adapted to pass through a selected hole in 25 said board and said member to adjustably connect them together, a pair of vertical mine jacks abutting the rear of said member, a pulley on the forward end of said board, a windlass adapted to be fastened 30 to the mine floor behind said jacks and a rope connected to the rear of said drill, passing around said pulley and connected to said windlass.

In testimony whereof I affix my signature.
MICHAEL P. STRETAUSKY.
